UNITED STATES PATENT OFFICE.

HENRY D. COHEN, OF NEWARK, NEW JERSEY.

DESIGN FOR A LENS FOR HEADLIGHTS.

50,682.

Specification for Design.

Patented May 1, 1917.

Application filed February 28, 1917. Serial No. 151,569. Term of patent 7 years.

To all whom it may concern:

Be it known that I, HENRY D. COHEN, a citizen of the United States, residing at Newark, county of Essex, and State of New Jersey, have invented a new, original, and ornamental Design for Lenses for Headlights, of which the following is a specification, reference being had to the accompanying drawing, forming part thereof.

Figure 1 is an elevation of the rear face of the lens.

Fig. 2 is a section on line 2—2 in Fig. 1, and

Fig. 3 is a section on line 3—3 in Fig. 1.

I claim:

The ornamental design for a lens for headlights, as shown.

HENRY D. COHEN.
